CLAIM

We claim, the ornamental design for an injection molding machine, as shown and described.

DESCRIPTION

FIG. 1 is a perspective view of an injection molding machine, showing our new design; and,

FIG. 2 is an enlarged partial view thereof.

Portions shown in broken lines form no part of the claimed design.

Color shown in FIG. 1 forms no part of the claimed design.

1 Claim, 2 Drawing Sheets

FIG. 1

FIG. 2
